(57) **CLAIM**

The ornamental design for an oval confectionary tablet with concave surface, as shown and described.

DESCRIPTION

FIG. 1 is a perspective view of an oval confectionary tablet with concave surface showing our new design;

FIG. 2 is a right side elevation view of the oval confectionary tablet with concave surface of FIG. 1, the left side elevation view being identical;

FIG. 3 is a front elevation view of the oval confectionary tablet with concave surface of FIG. 1, the rear view being identical;

FIG. 4 is a top plan view of the oval confectionary tablet with concave surface of FIG. 1; and,

FIG. 5 is a bottom plan view of the oval confectionary tablet with concave surface of FIG. 1.

The writing shown in broken lines in FIGS. 1 and 4 is for illustrative purposes only and forms no part of the claimed design.
